GAME APPARATUS

George Clarence Day, West Kennebunk, Maine

Application July 17, 1931. Serial No. 551,492

4 Claims. (Cl. 273—102)

This invention relates to a game apparatus and has for its primary object to provide, in a manner as hereinafter set forth, a device of this character which will require considerable skill in the successful playing thereof, and which will provide amusement or entertainment for persons playing the game or watching the game being played.

Other objects of the invention are to provide a game apparatus of the character described which will be simple in construction, strong, durable, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

20 Figure 1 is a view in front elevation of a device in accordance with this invention.

Figure 2 is a view in vertical section through the device.

25 Figure 3 is a fragmentary view in horizontal section and on an enlarged scale taken substantially on the line 3—3 of Figure 1 looking downwardly, as indicated by the arrows.

Figure 4 is a view of a metallic projectile to be used in playing the game.

30 Figure 5 is a detail view in perspective of one of the magnets.

Referring now to the drawings in detail it will be seen that the reference numeral 1 designates a substantially flat, rectangular panel of suitable 35 non-conducting material which is adapted to be disposed and supported in an inclined position by a brace 2 hingedly connected, as at 3, to an upper portion of the panel 1. The brace 2 is adapted to be detachably secured in operative 40 position relative to the panel 1 through the medium of an elongated hook 4 having its ends engaged with the lower end portion of the brace and with the lower end portion of the panel.

45 Mounted on the front or upper side of the panel 1 in spaced relation thereto is a metallic plate 5 which is secured to the panel and maintained in spaced relation thereto through the medium of the marginal flanges 6 which extend over the marginal edges of the panel 1 and are 50 secured thereto by suitable means, such as screws 7, as illustrated to advantage in Figure 3 of the drawings. Of course, the plate or front 5 may be of any suitable material other than metal. At spaced points in its area the plate 5 is provided 55 with inturned annular flanges 8 having their

free ends abutting the forward side of the panel 1 and defining circular pockets or shallow wells 9 which may, if desired, be of various diameters. The panel 1, of course, constitutes the bottoms or inner ends of the pockets or wells 9.

60 The panel 1 is provided, in each of the pockets or wells 9, and disposed below the centers of said pockets or wells, with a pair of openings 10 for the passage of the end portions of a substantially U-shaped magnet 11, the ends of

65 which project into the pockets or wells 9. The intermediate or bight portions of the magnets 11 are provided with openings 12 (see Figure 3) for the passage of the threaded shanks 13 which are anchored in the panel 1 between the openings 10 and which project rearwardly from said panel.

70 Coil springs 14 encircle the shanks 13 and have one end engaged with the panel 1 and their other ends engaged with the intermediate or bight portions of the magnets 11 for yieldingly urging

75 said magnets rearwardly relative to the panel. Winged adjusting nuts 15 are threaded on the outer end portions of the shanks 13 for engagement with the magnets 11 for adjusting said magnets toward the panel 1 against the tension

80 of the coil springs 14, as will be apparent from a consideration of Figure 3. Washers 16 encircle the shanks 13 and are interposed between the 85 adjusting nuts 15 and the magnets 11.

The reference numeral 17 (see Figure 4) designates a metallic projectile which is adapted to be thrown into the pockets or wells 9 and retained 90 therein by the magnets 11. The projectile 17 may be in the form of a plurality of metallic rings which are loosely interlooped or connected with each other. The front side of the panel 1 where exposed through the plate 5, may be suitably ornamented if desired.

95 In use, the player or players are provided with any desired number of the projectiles 17 which are thrown from any desired distance toward the board. The object, of course, is to throw the projectiles into the pockets or wells 9 and when this is accomplished the projectiles are attracted to the magnets 11 and in this manner retained 100 in the pockets or wells until removed.

A sheet 18, of suitable material such as heavy paper, cardboard or fabric, is interposed between the panel 1 and the plate 5 and is suitably ornamented on its forward side, the ornamental figures being exposed through the wells or pockets 9, as clearly seen in Figure 1 of the drawings. Any suitable ornamental figures may be provided on the sheet 18, such as the spots of playing cards or representations of animals or flowers.

It is believed that the many advantages of a structure in accordance with this invention will be readily understood, and although the preferred embodiment of the invention is as illustrated and described, it is understood, of course, that changes in the details of construction and in the combination and arrangement of parts may be resorted to which will fall within the scope of the invention as claimed.

10. What is claimed is:—

1. A game apparatus comprising a board, means for supporting the board, said board including a panel and a plate mounted on the panel in spaced relation thereto, annular flanges extending toward the panel from the plate and defining pockets in the board, said pockets for the reception of projectiles, and magnets mounted on the panel and disposed in the pockets for attracting the projectiles thereto and for retaining said projectiles in the pockets.

2. A game apparatus comprising a board, means for supporting the board, said board including a panel and further including a plate mounted on the panel in spaced relation thereto, marginal flanges on the plate secured to the panel, annular flanges on the plate extending toward and terminating in abutting engagement with the panel and defining annular pockets in the board, said pockets for the reception of metallic projectiles and magnets mounted on the panel for attracting the projectiles thereto and for retaining said projectiles in the pockets.

3. A game apparatus comprising a board, means for supporting the board, said board including a panel and further including a plate mounted on the panel in spaced relation thereto, marginal flanges on the plate secured to the panel, annular flanges on the plate extending toward

40.

and terminating in abutting engagement with the panel and defining annular pockets in the board, said pockets for the reception of metallic projectiles and magnets mounted on the panel for attracting the projectiles thereto and for retaining said projectiles in the pockets, said magnets being substantially U-shaped and having their end portions extending through the panel into the pockets and terminating in said pockets, and means for securing the magnets on the panel.

4. A game apparatus comprising a board, means for supporting the board, said board including a panel and further including a plate mounted on the panel in spaced relation thereto, marginal flanges on the plate secured to the panel, annular flanges on the plate extending toward and

80

85

90

95

terminating in abutting engagement with the panel and defining annular pockets in the board, said pockets for the reception of metallic projectiles and magnets mounted on the panel for attracting the projectiles thereto and for retaining said projectiles in the pockets, said magnets being substantially U-shaped and having their end portions extending through the panel into the pockets and terminating in said pockets, and means for securing the magnets on the panel, the last named means comprising threaded shanks anchored to the panel and extending through intermediate portions of the magnets, said magnets being adjustable longitudinally on the shanks, coil springs encircling the shanks and engaged with the magnets for yieldingly urging said magnets away from the panel, and winged nuts threaded on the shanks and engaged with the magnets for shifting said magnets against the tension of coil springs.
